UNITED STATES PATENT OFFICE.

CHARLES A. BREWER AND CLINTON G. SCANNELL, OF CHICAGO, ILLINOIS; SAID SCANNELL ASSIGNOR TO SAID BREWER.

VENDING DEVICE.

SPECIFICATION forming part of Letters Patent No. 780,086, dated January 17, 1905.
Application filed February 12, 1904. Serial No. 193,292.

To all whom it may concern:

Be it known that we, CHARLES A. BREWER and CLINTON G. SCANNELL, citizens of the United States, residing at Chicago, in the county of Cook and State of Illinois, have invented certain new and useful Improvements in Vending Devices, of which the following is a specification.

Our invention relates in general to vending devices, although combining therewith the character of an advertising appliance.

The object for which the invention is principally designed is to promote the introduction and sale of merchandise, principally of that class which is retailed in separate pieces or packages at a uniform price per piece or package—such, for instance, as chewing-gum, cigars, &c.—and this we accomplish through a novel mode and instrumentality of advertising and vending a line of goods involving the sale of orders for the goods, accompanied by orders for a limited number of premiums or gifts that are distributed with the goods.

The form which we have chosen as the preferred mechanical embodiment of the invention consists generally of a receptacle containing a series of pockets or holders for written or printed order-slips or equivalent order mediums, which latter are confined within the respective pockets or other holders of the receptacle by a frangible retaining device which serves to entirely conceal from sight the order itself, in association with an ejecting device by which the orders may one at a time be dislodged from the receptacle. In practice the receptacle itself will have prominently displayed thereon an announcement or advertisement of the goods for the sale of which it is instrumental, and the orders confined in the holders of the receptacle will call for a package or other fixed quantity of the article advertised, while a limited number of the holders may also contain orders for premiums or gifts, either separate articles or a certain value in trade. A customer will pay a certain sum—say five cents—for the privilege of ejecting or withdrawing an order from the device, which order will call for at least a quantity of the goods advertised to the retail-sale value

of the price paid for the privilege and in some instances for a premium or a gift. Preferably and as herein shown and described the series of order holders or containers will be sealed, and the orders themselves will be obtainable on the part of the customers by ejecting them from their sealed receptacles after paying the price charged for the privilege by means of the ejector, which breaks the frangible seal and removes the printed order-slips therefrom.

In the accompanying drawings we have illustrated a device well adapted to the carrying out of our invention, and referring thereto—

Figure 1 is a perspective view of the device in operative form and position, partly broken away to show underlying parts. Fig. 2 is a longitudinal sectional view of the device in folded position. Fig. 3 is a detail elevational view of the ejector. Fig. 4 is a detail perspective view of an order-slip in the rolled position which it assumes when in place in the holder, and Fig. 5 is a face view of the order-slip unrolled and exposed to view.

Referring to the drawings, A designates a plain flat rectangular board, constituting the chief element of the receptacle. Through the intermediate and lower end portion of this board are formed a series of apertures or holes a, which may be conveniently and cheaply made by boring. The upper end portion of the board is plain. Pasted or otherwise applied to the front and back sides of the board, so as to cover the ends of the holes a and preferably covering the entire surfaces of the board, are sheets B and C, respectively, of perforable material, preferably paper. The front sheet B has printed or otherwise indicated on its exposed face a series of circles b, preferably arranged in regular longitudinal and transverse rows and corresponding in number and relative location to the series of apertures in the board; so that each one of said circles directly covers and indicates the position of an underlying aperture. These circles have printed or otherwise indicated therein consecutive numbers preferably arranged in successive order either transversely

or longitudinally of the face of the board. The upper portion of the front sheet above the series of marked circles is plain and adapted to receive printed matter constituting an announcement or advertisement of the merchandise, the introduction and sale of which the device is intended to promote. This space may also contain printed directions for the manipulation of the device, as well as an announcement of premiums or gifts which accompany the sale of the goods advertised, where such are employed as an attractive feature of the device. The outer surface of the back sheet or covering C may, if desired, also be utilized for advertising purposes.

The holes *a* in the board are each designed to receive a medium for the announcement of an order for goods. This medium may take the form of any sort of a device capable of containing a printed or otherwise indicated order, but preferably and in the form herein shown consists of a slip of paper D, which has printed on one face thereof the name of the article or articles for which it calls—as, for instance, a package of gum. This slip is rolled up into the form shown in the detail view Fig. 4, preferably with the printed side inside, and the rolled slips thus bearing their orders for goods concealed from view are loaded into the several holders *a* of the board, after which the sheets B and C are applied to the latter, thus completely inclosing the rolled order-slips and constituting a seal therefor.

Fig. 3 indicates a convenient and preferred form of ejector consisting simply of a rod E of a diameter such as to loosely fit the holes of the board and of a length to extend at least partially through the board and its surface-coverings, with a knob or handle E' on one end thereof, this latter preferably having a flat face *e* at the end adjacent to the rod E. Some means for supporting the board in an inclined upright position for convenient manipulation with the ejector are preferably employed, such means as herein shown consisting of a back strut or brace in the form of a bent wire loop or bail F, the end portions of which are slightly offset and at their extremities bent inwardly and pivotally mounted in the edges of the board above the longitudinal center of the latter. Stop-pins G set into the sides of the board slightly below the pivots of the back strut engage the latter at the bends of the offsets when the board is set up and limit the angular movement of the back strut relatively to the board, at the same time permitting the parts to be folded or collapsed, as shown in Fig. 2.

From the foregoing it will be seen that the invention is essentially an order-vending device, although also adapted for the favorable display of advertising matter. The customer after having paid the price charged for the

privilege of obtaining one or more orders punches the stem of the ejector through one or more of the holes, the positions of which are indicated by the numbered circles on the face of the board, thus ejecting the order-slip, which on being unrolled exposes to view the name of the article or goods to which he is entitled for his purchase-money. If the order ejected by him calls for a premium or gift, such premium or gift is delivered to him by the salesman or other person in charge of the device without further expense. It is to be understood that all of the apertures are loaded with orders, each one of which represents goods of the retail value of the price paid for the privilege of manipulating the device, whether containing an order for a premium or not.

It is evident that the mechanical features of the device as herein shown and described might be considerably modified in details without departing from the spirit and substance of the invention. Hence we do not limit the latter to the particular mechanical form illustrated and described, except to the extent indicated in specific claims.

We claim—

1. In a device of the character described, the combination with a receptacle containing a series of apertures, of removable objects in said apertures, frangible means serving to retain said objects in place and concealing the same, and a device adapted to break said frangible retaining means, substantially as described.

2. In a device of the character described, the combination with a board containing a series of transverse perforations formed therethrough and a corresponding series of order mediums deposited in said perforations, of perforable covering-sheets applied to both sides of said board, and sealing the ends of said perforations, and an ejector in the form of a plug adapted to be inserted into said apertures to break the seals and eject the order mediums, substantially as described.

3. In a device of the character described, the combination with a board containing a series of transverse perforations formed therethrough, and a corresponding series of order mediums deposited in said perforations, of paper sheets applied to the opposite surfaces of said board, and sealing the perforations therein, a plug adapted to be thrust into said perforations to break their end seals and eject the order mediums therefrom, and a back strut supporting the board in operative position, substantially as described.

CHARLES A. BREWER.
CLINTON G. SCANNELL.
